UNITED STATES PATENT OFFICE.

GEORGE A. POSSON, OF ANGWIN, CALIFORNIA.

BRAKE-BLOCK.

SPECIFICATION forming part of Letters Patent No. 378,215, dated February 21, 1888.

Application filed November 1, 1887. Serial No. 253,959. (No model.)

To all whom it may concern:

Be it known that I, GEORGE ALLEN POSSON, of Angwin, in the county of Napa and State of California, have invented a new and Improved 5 Brake-Block, of which the following is a full, clear, and exact description.

The object of my invention is to provide a new and improved brake-block especially adapted for vehicles, and from which the brake-shoe can be easily and quickly removed when 10 worn out and a new one inserted.

The invention consists in the construction and arrangement of certain parts and details and combinations of the same, as will be fully 15 described hereinafter, and then pointed out in the claims.

Reference is to be had to the accompanying drawings, forming a part of this specification, in which similar letters of reference indicate 20 corresponding parts in all the figures.

Figure 1 is a perspective view of my improvement. Fig. 2 is a sectional side elevation of the same; and Fig. 3 is a perspective view of a modification of my improvement.

25 My improved brake-block A is made of two principal parts—the brake-shoe B and the back C, which is secured in any suitable manner to the brake-bar of the brake mechanism. The brake-shoe B may be of rubber, wood, or other 30 suitable material.

As shown in Figs. 1 and 2, I provide the back C on its upper part with two sidewise-extending flanges, H, fitting over the sides of the brake-shoe B. A bolt, I, passes through 35 said flanges and through the brake-shoe B transversely, thus holding the upper part of the brake-shoe in place in the back C. The lower end of the latter is provided with a flange, J, passing under the bottom of the brake-shoe 40 B, and provided on its inner end with an upwardly-pointed projection, J', driven into a groove in the bottom of the brake-shoe B, so that the lower part of the latter is also held securely in place on the back C. The latter 45 is also provided with the rearwardly-extending bolts K, by which the brake-block is secured to the brake-bar.

For buggies and spring-wagons the metallic back will be made in two halves, as if cut

through from top to bottom, and each half is 50 provided on its flange H with projections or hooks L, passing into apertures on the sides of the brake-shoe B, in place of the bolt I, mentioned above, thus holding the shoe between the two parts, as in the jaws of a vise. Each 55 half is also provided with ribs N, fitted onto the brake-bar, and provided with apertures through which passes a bolt for holding the halves on the brake-shoe and the brake-block 60 on the brake-bar.

In the construction shown in Figs. 1 and 2 the brake-shoe B may be removed by simply withdrawing the bolt I and then lifting the brake-shoe B upward until it disengages the point of projections J. A new shoe is then 65 fitted onto the back C, driven onto the projections J', and the bolt I is replaced, whereby said shoe is again securely fastened in place on the back C.

Having thus described my invention, what 70 I claim as new, and desire to secure by Letters Patent, is—

1. The combination, with a brake-shoe, B, of a metallic back formed with upper side flanges, H, embracing the sides of the block, and with 75 bottom flange, J, having upward-projecting points J' entering the lower end of the shoe, substantially as set forth.

2. As a new article of manufacture, a back 80 for brake-shoes comprising the metal plate C, formed with upper side lugs, H, the bottom flange, J, having points J', and the attaching-bolts K, projecting from the rear face of said plate, substantially as set forth.

3. The combination, with a brake-shoe, of a 85 back provided at its upper end with flanges fitting over the sides of said brake-shoe, a bolt passing through said flanges and through said brake-shoe transversely, a flange formed on the lower end of said back and provided with 90 upwardly-projecting lugs passing into the bottom of the brake shoe, substantially as shown and described.

GEORGE A. POSSON.
